UNITED STATES PATENT OFFICE.

JESSE C. WILLIAMS, OF MARSHALLTOWN, IOWA.

PLASTERER'S HAWK.

Application filed July 11, 1922. Serial No. 574,141.

To all whom it may concern:

Be it known that I, JESSE C. WILLIAMS, a citizen of the United States, and a resident of Marshalltown, in the county of Marshall and State of Iowa, have invented a certain new and useful Plasterer's Hawk, of which the following is a specification.

The object of my invention is to provide a plasterer's hawk of simple, durable and inexpensive construction in which the body portion may be formed of a single piece of sheet metal and the handle detachably connected therewith in such a manner that the handle and body may be readily removed for convenience in shipping, handling and storing, and also readily, quickly and easily connected with each other, and when connected will be firmly and immovably united; and

Further to provide a device of this kind in which all of the parts are permanently connected either to the handle member or the body member so that the smaller connecting members cannot become lost or misplaced in shipping or storing.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a perspective view of my improved plasterer's hawk with the handle and the body portion assembled.

Figure 2 shows a perspective view of the socket holding plate detached.

Figure 3 shows a perspective view of the socket for clamping the plate and handle together; and

Figure 4 shows a vertical, central, sectional view of the complete device assembled.

Referring to the accompanying drawings, I have used the reference numeral 10 to indicate the body portion or plate of my improved plasterer's hawk, which is preferably made of a single piece of sheet metal such as aluminum of proper size and thickness.

For connecting the body portion to the handle, I have provided a socket holding plate indicated generally by the numeral 11. This plate is also preferably formed of a piece of sheet metal, and its central portion is formed with a circular depression at 12, and in the center of the circular depression is a rectangular opening 13. Around the

edges of the plate are left openings 14. This plate is permanently connected to the body portion 10 of the hawk by rivets 15, the ends of the rivets being ground flush with the upper face of the hawk body.

For connecting the handle with the plate I provide a socket member comprising a base 16 with a rectangular raised portion 17 formed on one side of it, and a cylindrical socket member 19 at the center of the portion 17. The socket member is internally screw threaded. The thickness of the base 16 corresponds with the depth of the depression 12 in the plate 11, and the part 17 is of such size as to freely enter and fit into the rectangular opening 13. This member is, of course, placed in position within the depression of the socket holding plate before the latter is riveted to the hawk body.

The handle is preferably formed of a body portion 20 which may be made of wood, and has a circular opening extending through it to receive the bolt 21. The head of the bolt 22 reinforces and protects the outer end of the wooden handle and the bolt is prevented from rotation within the wooden handle by means of the teeth 23 formed on the bolt near its head, which teeth are forced into the handle.

At the opposite end of the handle there is an enlarged cylindrical opening at 24 designed to receive the cylindrical socket 18. The screw threaded end of the bolt is designed to enter the screw threaded interior of the socket 18.

In assembling the device the socket, which may be cast complete in one piece, is placed loosely within the socket holding plate, and the latter is riveted to the hawk body. This may be accomplished readily and quickly and with slight expense, because it is not necessary that the socket member accurately fit in the socket holding plate. It is only necessary that the heads of the rivets which project through the socket holding plate be ground off smooth with the surface of the plate.

The handle is cheap and inexpensive because it consists only of the wood handle and the bolt. However, the bolt is permanently fixed to the handle and hence there are only two parts to the device, to wit: the body portion and the handle portion. The handle may be readily and easily removed for shipping, packing or storing.

In order to assemble the device, it is only

necessary to place the screw threaded end of the bolt into the screw threaded socket and then turn the handle until the end of the handle engages the socket holding plate, then 5 by tightening the handle the edges of the socket enter the plate surrounding the screw threaded opening 13 and firmly clamps the base of the socket holding plate and the adjacent end of the handle. In this manner, any 10 lost motion that there might be between the socket and the socket holding plate is taken up and the parts are firmly united, but the handle may be removed without the use of tools, by simply unscrewing it.

15 I claim as my invention:

1. An improved plasterer's hawk comprising a body portion having a flat face to receive plaster, a socket holding plate fixed to the under surface of the body and formed 20 with a depression at its central portion having an angular opening therein, a socket device having a base to be received in the said depression and an angular projection to be received in said angular opening and a cylindrical internally screw threaded socket projecting beyond said opening, a handle member comprising a handle proper having a screw threaded rod therein and an annular 25 recess formed in the handle surrounding the screw threaded portion of the bolt and designed to receive the said cylindrical socket, said parts being so shaped and proportioned 30 that as the bolt is screwed into the socket, the handle will engage the socket holding plate and cause the socket holding plate to be clamped between the base of the socket and the adjacent end of the handle, and means for fixing the bolt against movement 35 relative to the handle.

that as the bolt is screwed into the socket, the handle will engage the socket holding plate and cause the socket holding plate to be 35 clamped between the base of the socket and the adjacent end of the handle.

2. An improved plasterer's hawk comprising a body portion having a flat face to receive plaster, a socket holding plate fixed to the under surface of the body and formed with a depression at its central portion having an angular opening therein, a socket device having a base to be received in the said depression and an angular projection to be received in said angular opening and a cylindrical internally screw threaded socket projecting beyond said opening, a handle member comprising a handle proper having a screw threaded rod therein and an annular 50 recess formed in the handle surrounding the screw threaded portion of the bolt and designed to receive the said cylindrical socket, said parts being so shaped and proportioned 55 that as the bolt is screwed into the socket, the handle will engage the socket holding plate and cause the socket holding plate to be clamped between the base of the socket and the adjacent end of the handle, and means for fixing the bolt against movement 60 relative to the handle.

Des Moines, Iowa, June 9, 1922.

JESSE C. WILLIAMS.
